JASPER VAN WORMER AND MICHAEL McGARVEY, OF ALBANY, NEW YORK.

Design No. 2,781, dated September 10, 1867.

DESIGN FOR A PARLOR-STOVE.

The Schedule referred to in these Letters Patent and making part of the same.

Be it known that we, JASPER VAN WORMER and MICHAEL McGARVEY, of Albany, State of New York, have produced a new ornamental Design for the Plates of a Hall or Parlor-Stove; and we declare the annexed drawing, exhibiting in perspective a stove with the plates in place, to be a full and accurate delineation of the said plates with their ornaments, the parts not exhibited being symmetrically similar to those shown.

What we claim as our production, and desire to secure by Patent, is—

The ornamental design for a hall or parlor-stove, as shown and described.

JASPER VAN WORMER,
MICHAEL McGARVEY.
